BRAKING MECHANISM

John Blewett, Dallas, Tex., assignor to The Murray Company, Dallas, Tex., a corporation of Texas

Application September 16, 1935, Serial No. 40,704

13 Claims. (Cl. 188—74)

This invention relates to new and useful improvements in braking mechanism.

One object of the invention is to provide an improved braking mechanism which is particularly adapted for use in halting the rotation of the huller picker roller shaft of a cotton gin.

An important object of the invention is to provide an improved braking mechanism for the huller picker roller shaft of a cotton gin including a brake shoe which is mounted in fixed relation to the drive wheel of said shaft, whereby when the gin breast which carries the shaft and wheel is swung for any reason, said drive wheel moves into engagement with the shoe to halt rotation of said shaft, thereby automatically stopping rotation of the picker roller when the breast is swung, whereby the ejection of cotton by the picker roller into the hull and seed conveyor is prevented when the breast is lifted.

Another object of the invention is to provide an improved braking mechanism for the huller picker roller shaft of a cotton gin, which includes a pivoted brake shoe located to be engaged by the drive wheel of said shaft, the pivotal mounting of said shoe permitting the latter to automatically align itself so as to have its curved braking surface complementary to the periphery of the wheel at all times, whereby an adjustment forwardly and rearwardly of the picker roller shaft will not move the drive wheel out of alignment with said shoe, thereby assuring proper braking regardless of the position of the picker roller shaft.

Still another object of the invention is to provide a braking mechanism having a shoe arranged to engage the drive wheel of the picker roller shaft of a cotton gin, the shoe being mounted so as to be readily adjustable with relation to the periphery of the drive wheel, whereby the gin breast must be swung a predetermined distance before the brake shoe engages the wheel to stop rotation of the shaft.

Still another object of the invention is to provide an improved braking mechanism which is simple in construction and cheap in manufacture, and which may be readily applied to any standard type of cotton gin without changing the structure thereof.

A construction designed to carry out the invention will be hereinafter described, together with other features of the invention.

The invention will be more readily understood from a reading of the following specification and by reference to the accompanying drawing, in which an example of the invention is shown, and 55 wherein:

Figure 1 is a side elevation of a cotton gin, showing a braking mechanism constructed in accordance with the invention attached thereto.

Figure 2 is an enlarged elevation of the braking mechanism and a portion of the drive wheel 5 for the picker roller shaft.

Figure 3 is a front elevation of the parts shown in Figure 2.

Figure 4 is a transverse, vertical, sectional view taken through the drive wheel and showing the 10 mechanism in braking position, and,

Figure 5 is an isometric view of the brake shoe.

In the drawing, the numeral 10 designates the forward portion of an ordinary cotton gin. The gin may be constructed in the usual way and is 15 provided with the usual gin breast 11 at its forward end. The breast is pivoted at a point 13 at the upper end of the gin, whereby when said breast is swung its lower end moves outwardly away from the gin proper. The usual ginning 20 saws (not shown) are mounted transversely within the gin on the transverse saw shaft 14. The lower end of the gin breast 11 is formed with an angular slot 15 in each of its side walls, and the transverse picker roller shaft 16 is suitably 25 mounted in these slots in the usual way.

On the outer end of the picker roller shaft 16, an enlarged drive wheel or pulley 17 is mounted. A suitable drive belt 18 passes around the under- 30 side of the drive pulley 17 and the other end of this belt has a driving connection over idle pulleys carried by the gin frame 10 with the gin saw shaft 14 which is driven by any suitable driving mechanism (not shown), whereby the picker roller shaft 16 is rotated. The shaft 16 is pro- 35 vided with a small pulley 19 which is located between the inner sides of the drive wheel 17 and the end wall of the gin breast 11. An endless belt 20 passes around the pulley 19 and over a second pulley 21 which is mounted on the outer end of 40 a transverse shaft 22 which extends transversely through the gin breast 11 above the picker roller. The shaft 22 carries the usual kicker roller (not shown) thereon. It is obvious that when the drive belt 18 is being driven by the drive mecha- 45 nism (not shown) the drive wheel 17 is rotated to revolve the picker roller shaft 16 which in turn revolves the picker roller (not shown). When the shaft 16 is rotated through the drive wheel 17, motion is also imparted to the kicker roller shaft 22 through the medium of the pulleys 19 and 21. To keep the driving belt 20 which connects these latter two pulleys taut at all 50 times a spring-pressed idler roller 23 is pivoted on the outer end of the gin breast 11. All of the 55

above parts which have been described are of the usual construction and are present in the ordinary cotton gin. Therefore, these parts are subject to variation, and form no particular part 5 of the invention.

In carrying out the invention, a vertical bracket 25 is suitably fastened by bolts to the side of the frame proper of the cotton gin 10. This bracket has its upper end extending upwardly 10 in a plane above the upper edge of the drive wheel 17 and has a horizontal arm 26 pivoted thereto. This arm extends forwardly from the bracket and is formed with an outwardly extending bearing collar 27 at its extreme outer end. The outer 15 end of the collar 27 overlies the upper end of the drive wheel 17 and a brake shoe 28 has its upper end pivoted on a pin 29 to this outer end, as is clearly shown in Figure 3. The brake shoe is clearly shown in Figure 5 and is preferably made 20 of a casting and is formed with an arcuate braking surface 28' at its lower end. The arc of the braking surface 28' is complementary to the curved outer periphery of the drive wheel 17.

An inclined pin 29' extends through the outer 25 end of the pivoted arm 26 and this pin has its outer end screw-threaded to receive a thumb nut 30. The pin extends through the outer end of said arm and has its lower end secured to one end of a coil spring 31 which has its other end 30 suitably fastened in the lower end of the bracket 25. It will be obvious by observing Figures 2 and 4, that the coil spring 31 exerts its pressure to pull the outer end of the pivoted arm 26 downwardly, whereby the arcuate braking surface 28' 35 of the brake shoe 28 will be pulled into engagement with the periphery of the drive wheel 17. The provision of the thumb nut 30 on the upper screw threaded end of the pin 29 provides a simple means for varying the tension which the spring 40 may exert upon the outer end of said arm.

For limiting the downward swing of the arm 26, and the brake shoe 28 carried thereby, a vertical set screw 32 is threaded through the arm 26 nearer its inner end. The lower end of this 45 set screw is arranged to engage a horizontal forwardly extending arm 33 which is preferably made integral with the bracket 25. A suitable lock nut 34 is threaded on the set screw 32, as is clearly shown in Figure 2. It will be obvious that 50 by adjusting the set screw 32 that the downward movement of the pivoted arm 26 and the brake shoe pivoted to the outer end thereof is limited. By adjusting the screw 32 the arcuate braking surface 28' of the brake shoe 28 may be spaced a 55 desired distance from the periphery of the drive wheel 17. As shown in Figure 2 the set screw 32 has been adjusted so that there is a slight space between the periphery of said drive wheel and the underside of the arcuate braking surface 28'. If the set screw were tightened or 60 screwed downwardly through the pivoted arm 26 a greater distance, then it would be obvious that the pivoted arm 26 would be raised, which would result in raising the brake shoe 28, whereby a 65 greater space would be provided between the underside of the braking surface 28' of said shoe and the outer periphery of the drive wheel 17. The adjustment on the set screw 32 may be accomplished quickly and easily by merely loosening the lock nut 34. The tension which the 70 spring exerts against the outer end of the pivoted arm 26 may be readily varied by adjusting the wing nut 30 on the upper threaded end of the pin 29 to which the upper end of the coil spring 75 31 is secured.

In operation, the set screw 32 is adjusted so that the arcuate braking surface 28' of the brake shoe 28 is spaced a slight distance from the outer periphery of the drive wheel 17 when the gin breast 11 is swung to its inner or closed position as shown in full lines in Figure 1. In this 5 position operation of the driving mechanism of the gin is accomplished in the usual way, with the driving mechanism (not shown) operating the drive belt 18 to rotate the drive wheel 17, whereby the picker roller (not shown) and the kicker roller (not shown) are operated. However, when the gin breast 11 is swung to empty the contents of the roll box of said gin, or for any other reason, it is desirable to stop the rotation of the 10 picker roller shaft 16 because it may be necessary for the operator to reach within the gin breast to clean said breast of trash or other extraneous matter. For this reason the picker roller should be halted. It will be seen that when the gin breast 11 is swung, said breast will swing from its pivot point 13 at the upper end of the gin. Since the picker roller shaft 16 and drive wheel 17 secured to its outer end is mounted in the angular slot 15 in the lower end of said breast, said shaft and 25 drive wheel will swing with the breast in an arc as shown by the dotted lines in Figure 1. This will cause the drive wheel 17 to swing upwardly into engagement with the arcuate braking surface 28' of the brake shoe, as is shown in Figure 30 4. Since the brake shoe 28 is pivoted at its upper end to the bearing collar 27, it will be obvious that the braking surface 28' will readily engage the periphery of the drive wheel 17 because the arcuate braking surface is on the same arc as 35 the periphery of said wheel. As soon as the brake shoe 28 engages the periphery of the wheel, it will be seen that the rotation of said wheel will be stopped, which will halt the rotation of the picker roller shaft 16. If the breast 11 continues 40 to swing outwardly after the periphery of the drive wheel 17 has engaged the arcuate braking surface 28', this engagement will not interfere with the further swinging of said gin breast because further movement of said breast will cause 45 the pivoted arm 26 to be swung upwardly under tension of the spring 31 which will be expanded. This will only serve to increase the pressure of the arcuate braking surface 28' of the brake shoe against the periphery of the drive wheel 17. 50 Therefore, it will be seen that the brake will not in any way interfere with the swinging of the breast 11.

Of course, as the breast 11 is returned to its normal position the arm 26 will move downwardly as far as the set screw 32 will permit. Thus, the parts will be returned to their normal position, there being a slight space between the braking surface 28 of the brake shoe and the periphery of the drive wheel 17. Therefore the 60 operation of the gin can be continued in the usual way. It is noted that it is desirable to swing the breast 11 outwardly for various reasons and in the course of a day when the gin is operating full time, the breast may be swung innumerable 65 times. With the braking arrangement disclosed above, the braking of the picker roller shaft is automatically accomplished each time the breast is swung without interfering with the other operating parts of the gin, since upon swinging 70 the breast the driving tension of belt 18 is released. The ginning saws and other operating parts of the gin 10 may continue to operate throughout the swinging of the gin breast 11.

It is noted that the picker roller shaft may be 75

adjusted forwardly and rearwardly of the gin by movement in the slot 15. This movement adjusts the picker roller with relation to the huller ribs (not shown) of the gin in the usual way. It is obvious that as said picker roller shaft is moved within the slot, the drive wheel 17 will of course, be moved. The pivotal mounting of the brake shoe will permit said shoe to be swung with the movement of the drive wheel, whereby the 10 braking surface 28' is always complementary to the periphery of said wheel. The pivotal connection of the shoe with its supporting arm provides for a self-alignment of the shoe when the drive wheel is moved due to an adjustment of the 15 picker roller. This is one of the features of the invention.

The braking mechanism disclosed is simple in construction and cheap to manufacture. There are a minimum of parts and adjustments may be 20 readily made. It is noted that after the set screw 32 has been adjusted a single time and the wing nut 30 has properly adjusted the tension of the spring 31, the parts need no further attention. Of course, as the spring becomes weaker 25 through wear or a greater braking pressure is desired on the periphery of the drive wheel, the wing nut 30 may be adjusted to increase the tension of the spring 31. It is further noted that the set screw 32 may be adjusted so that 30 the breast 11 will have to move a predetermined distance before the braking action takes place. This is obvious because if the screw 32 is adjusted so that there is a greater space between the underside of the arcuate braking surface 28' and 35 the periphery of the drive wheel 17, then said drive wheel will have to move or swing a greater distance before the braking action takes place. Similarly, if the set screw is adjusted to reduce the space between the braking surface 28' and the periphery of said wheel then a slight movement of said wheel or a slight swinging of the 40 gin breast 11 will cause the brake shoe 28 to halt the rotation of the drive wheel.

What I claim and desire to secure by Letters Patent is:

1. A braking mechanism for a cotton gin including, an immovable support secured to the fixed frame of said gin, an arm having one end pivoted to said support and extending adjacent the drive wheel of the picker roller shaft of said 50 gin, said arm being located in a plane above said drive wheel, and a brake shoe carried by the outer end of said arm and arranged to be engaged by said drive wheel when the latter is moved due to the swinging of the breast of said 55 gin which carries the picker roller.

2. A braking mechanism for the picker roller shaft of a cotton gin including, an immovable support secured to the fixed frame of said gin, an arm having one end pivoted to the support and extending forwardly therefrom, a brake shoe carried by the outer end of said arm and arranged to be engaged by the periphery of the drive wheel of said picker roller shaft when said wheel is moved upwardly due to the swinging of the breast of 60 said gin, resilient means exerting its pressure to hold the shoe against the wheel when the same has moved into engagement therewith, and means for normally supporting the shoe out of engagement with the 65 drive wheel.

3. A braking mechanism for the picker roller shaft of a cotton gin including, a support secured to the fixed frame of said gin, an arm having one end pivoted to the support and extend-

ing forwardly therefrom, a brake shoe carried by the outer end of said arm and arranged to be engaged by the periphery of the drive wheel of said picker roller shaft when said wheel is moved upwardly due to the swinging of the breast of 5 said gin, and means for limiting the downward movement of the arm and brake shoe carried thereby, whereby when the gin breast is in its closed position the brake shoe is out of engagement with said drive wheel.

4. A braking mechanism for the picker roller shaft of a cotton gin including, a support secured to the fixed frame of said gin, an arm having one end pivoted to the support and extending forwardly therefrom, a brake shoe carried by the 15 outer end of said arm and arranged to be engaged by the periphery of the drive wheel of said picker roller shaft when said wheel is moved upwardly due to the swinging of the breast of 20 said gin, a stop for limiting the downward movement of the arm and brake shoe carried thereby, whereby when the gin breast is in its closed position the brake shoe is out of engagement with said drive wheel, and resilient means for holding 25 the arm against this stop.

5. A braking mechanism for the picker roller shaft of a cotton gin including, a support secured to the fixed frame of said gin, an arm having one end pivoted to the support and extending forwardly therefrom, a brake shoe carried by the 30 outer end of said arm and arranged to be engaged by the periphery of the drive wheel of said picker roller shaft when said wheel is moved upwardly due to the swinging of the breast of 35 said gin, and adjustable means for limiting the downward movement of the arm and brake shoe carried thereby, whereby the space between the brake shoe and the drive wheel may be varied so that the wheel will have to move a predetermined distance before engaging said brake shoe. 40

6. A braking mechanism for the picker roller shaft of a cotton gin including, a support secured to the fixed frame of said gin, an arm having one end pivoted to the support and extending forwardly therefrom, a brake shoe carried by the 45 outer end of said arm and arranged to be engaged by the periphery of the drive wheel of said picker roller shaft when said wheel is moved upwardly due to the swinging of the breast of 50 said gin, a stop for limiting the downward movement of the arm and brake shoe carried thereby, whereby when the gin breast is in its closed position the brake shoe is out of engagement with said wheel, a coil spring engaging the outer end of the arm and exerting its pressure to hold said 55 arm against its stop, and means for varying the tension on the coil spring.

7. A braking mechanism for the picker roller shaft of a cotton gin including, a support secured to the fixed frame of said gin, an arm having one 60 end pivoted to the support and extending forwardly therefrom, a brake shoe carried by the outer end of said arm and arranged to be engaged by the periphery of the drive wheel of said picker roller shaft when said wheel is moved 65 upwardly due to the swinging of the breast of said gin, a projection at the upper end of the support and extending beneath the pivoted arm, a set screw threaded through said arm and having its lower end arranged to engage the projection 70 whereby the downward movement of said arm and brake shoe carried thereby is limited, and resilient means for holding the arm in its downward position whereby the lower end of said set screw is held in engagement with the projection. 75

8. A braking mechanism for the picker roller shaft of a cotton gin including, a support secured to the fixed frame of said gin, an arm having one end pivoted to the support and extending forwardly therefrom, a brake shoe carried by the outer end of said arm and arranged to be engaged by the periphery of the drive wheel of said picker roller shaft when said wheel is moved upwardly due to the swinging of the breast of said gin, a projection at the upper end of the support and extending beneath the pivoted arm, a set screw threaded through said arm and having its lower end arranged to engage the projection whereby the downward movement of said arm and brake shoe carried thereby is limited, a coil spring having one end secured to the outer end of the pivoted arm and its other end secured to the lower end of said support, the spring exerting its tension to hold the lower end of the set screw against the projection, and means for varying the tension on said spring.

9. A braking mechanism for a cotton gin including, a support secured to the fixed frame of said gin, an arm having one end pivoted to said support and extending adjacent the drive wheel of the picker roller shaft of said gin, said arm being located in a plane above said drive wheel, and a brake shoe pivoted to the outer end of said arm and arranged to be engaged by said drive wheel when the latter is moved due to the swinging of the breast of the gin which carries the picker roller shaft, the pivotal mounting of said shoe permitting the same to be self-aligning with relation to the periphery of the drive wheel when the latter is moved due to the adjustment of the picker roller shaft with relation to the huller ribs of said gin.

10. A braking mechanism for a cotton gin including, a support secured to the fixed frame of said gin, an arm having one end pivoted to said support and extending adjacent the drive wheel of the picker roller shaft of said gin, said arm being located in a plane above said drive wheel, a brake shoe pivoted to the outer end of said arm and arranged to be engaged by said drive wheel when the latter is moved due to the swinging of the breast of the gin which carries the picker roller shaft, the pivotal mounting of said shoe permitting the same to be self-aligning with relation to the periphery of the drive wheel when the latter is moved, and resilient means exerting its pressure to hold the shoe in engagement with

the wheel when the latter has moved into contact therewith.

11. A braking mechanism for a cotton gin including, a support secured to the fixed frame of said gin, an arm having one end pivoted to said support and extending adjacent the drive wheel of the picker roller shaft of said gin, said arm being located in a plane above said drive wheel, a brake shoe pivoted to the outer end of said arm and arranged to be engaged by said drive wheel when the latter is moved due to the swinging of the breast of the gin which carries the picker roller shaft, the pivotal mounting of said shoe permitting the same to be self-aligning with relation to the periphery of the drive wheel when the latter is moved, resilient means exerting its pressure to hold the shoe in engagement with the wheel when the latter has moved into contact therewith, and means for limiting the downward movement of said brake shoe and arm, whereby when the gin breast is in a closed position, said shoe is out of engagement with said drive wheel.

12. In a cotton gin, the combination with a fixed frame member of the gin, a swinging breast pivotally connected therewith, a gin saw with its shaft journaled in the fixed frame, picker rollers having their shafts drivingly connected with each other and journaled in said swinging breast, pulleys on said saw shaft and one of said picker roller shafts, idle pulleys above last pulleys and supported by the fixed gin frame, and a belt connecting said saw shaft and picker shaft pulleys and extending over the idle pulleys whereby the belt is tensioned for driving the picker rollers when the breast is in its lowered closed position, of a brake pivotally supported by the gin fixed frame and adapted to be engaged by the picker roller pulley to stop the rotation of the picker rolls when the breast is swung upwardly to open position and thereby releasing the tension on said driving belt.

13. A braking mechanism for a cotton gin including, a support adapted to be immovably fastened to the stationary frame of a cotton gin, a stop on said support, and a brake shoe carried by the support and arranged to move into braking engagement with the drive wheel of the picker roller shaft of said cotton gin to stop the rotation of said shaft when the breast of said gin is swung to an open position, said shoe being normally supported by said stop out of braking position.

JOHN BLEWETT.
